UNITED STATES PATENT OFFICE.

ERNEST W. ROBEY, OF LONDON, ENGLAND, ASSIGNOR TO UNDERFEED STOKER COMPANY LIMITED, OF LONDON, ENGLAND.

ASH-CONVEYING MECHANISM.

Application filed November 10, 1919. Serial No. 337,082.

To all whom it may concern:

Be it known that I, ERNEST WILLIAM ROBEY, a subject of the King of Great Britain, residing in London, England, have 5 invented certain new and useful Improvements in Ash-Conveying Mechanism, of which the following is a specification.

In operating furnaces of the kind in which the ashes are discharged into a conveyor operating under water which acts as a seal to prevent access of air to the furnace, there is the difficulty that should the conveyer be put out of work for any reason, provision must be made for continuing the 10 removal of ashes and it becomes a problem how to do this without admitting air to the furnace.

By the present invention the submerged conveyer is duplicated each conveyor being 15 separately operated and a device is provided with means by which the ashes can be diverted from the point of discharge so that they fall into either conveyer accordingly as the device is set for their travel in 20 one direction or the other. Thus, should one conveyer be thrown out of operation, the other can be brought into use by merely setting the said device, and removal of ashes continues without disturbing the water seal.

25 Three constructions are shown in the accompanying drawings as examples of the invention.

Fig. 1 is a cross section through a trough containing water which seals a discharge 30 hopper, the trough containing two conveyers.

Fig. 2 is a cross section through a trough containing water and two conveyers, the trough being built in a furnace setting and serving a number of travelling grates.

40 Fig. 3 is a diagrammatic longitudinal section through one of the conveyers on line 3-3 of Fig. 2.

Fig. 4 is a cross section through two parallel troughs, each containing water and a conveyer, and each trough serving a common discharge hopper.

Referring to Fig. 1, the bottom of the trough *a* has tracks for two conveyers *b* at a suitable distance apart. The conveyers here shown are of the endless chain type, travelling up inclines at the ends of the trough and returning beneath the latter. The trough is adapted to hold water of sufficient depth to seal the discharge hopper *c*, and is of length suitable for serving sev-

eral such hoppers. Co-incidently with the longitudinal middle line of the trough is mounted a shaft *d* adapted to be turned on its axis by the lever *e* and carrying beneath each hopper a plate *f* of length sufficient to 60 extend at an incline, from one edge of the rectangular mouth of the hopper to the opposite conveyer as indicated in the drawing. Thus the plate guides the ashes and clinker to the conveyer in use; when it is 65 desired to use the other conveyer the lever *e* is turned so that plate *f* may have the position indicated in dotted lines.

Referring to Fig. 2 the trough *a'* serves a number of travelling grates *g*. The trough 70 is divided by a longitudinal partition *h* and each compartment contains an endless chain conveyer *b'* travelling in the trough and submerged for the greater part of its length in the water therein. As in the case of Fig. 75 1 a longitudinal shaft *d'*, mounted to be turned on its axis by a lever *e'* carries a flap *i* at the place of discharge of each grate *g*. When this flap has the position shown in full lines the ashes are discharged into 80 the left hand compartment of the trough where they fall through the upper length of the conveyer to be carried away by the lower length. When the flap is turned into the position shown in dotted lines the right 85 hand conveyer receives the ashes. Between adjacent grates a vertical plate *m* extends below the surface of the water in the trough to seal the discharge passage. The endless chains of the conveyer, one of which chains 90 is seen at *b'* in Fig. 3 travel over front and rear sprocket wheels *C* and *K* respectively and are guided by pulleys *l* and *n*. The front sprockets *C* are suitably driven and the axle of the rear sprockets *K* is mounted 95 in a lever frame *o* adapted to be adjusted in position by screw spindle *p* for tensioning the chains.

Referring to Fig. 4 the hopper *c²* has two discharge chutes, one over each trough *a²*. As before the troughs serve a number 100 of hoppers. The endless chain conveyers *b²* return below the troughs as in Fig. 1. On the drawing the left hand chute is discharging the hopper, the door *k²*, controlled by a lever (not shown) being in open position, while the corresponding door *l²* of the right hand chute is closed.

Having thus described the nature of the 110 said invention and the best means I know

of carrying the same into practical effect,
I claim:—

1. In combination, a furnace setting, a travelling grate therein, means adapted to contain water, baffles extending from said setting into the water space thereof to seal the grate from access of air, two parallel chain type conveyors in said water space, and means adapted to direct ashes from said grate continuously into either conveyor.
2. In combination, a furnace setting, a travelling grate therein, a trough adapted to contain water, means extending from said setting into the water space of said trough to seal the grate from access of air, two parallel conveyors of the endless chain type in said trough beneath the water level thereof, and means adapted to direct ashes from the grate continuously into either conveyor.

3. In combination, a furnace setting, a travelling grate therein, an end wall on said setting, a trough adapted to contain water constructed in said setting, means depending from said end wall into the water space of said trough to seal the grate from access of air, a longitudinal partition dividing said trough into two compartments, an ash conveyor of the endless chain type disposed in each compartment below the water level thereof, a support between the compartments, a plate mounted to turn on an axis in the support parallel to said partition, and means for positioning the plate so as to direct ashes from the grate continuously into either compartment.

In testimony whereof I have signed my name to this specification.

E. W. ROBEY
